UNITED STATES PATENT OFFICE.

JOHN D. KARLE, OF ROSELLE PARK, NEW JERSEY, ASSIGNOR TO THE SINGER MANUFACTURING COMPANY, A CORPORATION OF NEW JERSEY.

DESIGN FOR A BELT-FAN.

53,967.

Specification for Design.

Patented Oct. 14, 1919.

Application filed April 25, 1919. Serial No. 292,752. Term of patent 14 years.

To all whom it may concern:

Be it known that I, JOHN D. KARLE, a citizen of the United States, residing at Roselle Park, in the county of Union and State of New Jersey, have invented a new, original, and ornamental Design for Belt-Fans, of which the following is a specification, reference being had therein to the accompanying drawings.

The figure is a perspective view of a belt fan, showing my new design.

I claim:

The ornamental design for a belt fan, as shown.

In testimony whereof, I have signed my name to this specification.

JOHN D. KARLE.
